Christopher C. Warren

UNITED STATES PATENT OFFICE.

CHRISTOPHER COLUMBUS WARREN, OF CHUNKEY'S STATION, MISSISSIPPI,
ASSIGNOR OF ONE-HALF TO NANCY WARREN, OF SAME PLACE.

BOLT-EXTRACTOR.

SPECIFICATION forming part of Letters Patent No. 433,380, dated July 29, 1890.

Application filed March 7, 1890. Serial No. 343,007. (No model.)

To all whom it may concern:

Be it known that I, CHRISTOPHER COLUMBUS WARREN, a citizen of the United States, residing at Chunkey's Station, in the county 5 of Newton and State of Mississippi, have invented a new and useful Bolt-Extractor, of which the following is a specification.

This invention has relation to a device for extracting bolts from bolt-holes; and among 10 the objects in view are to provide a strong and durable device so constructed as to grip a bolt and draw the same from the hole in which it is contained in such a manner as to prevent marring or otherwise injuring the 15 threads or body portion of the bolt.

With the above objects in view the invention consists in a bar or lever one end of which is chamfered to take under the head of the bolt and start the same and the opposite end 20 of which is oppositely beveled or reduced, provided at each side with fulcrum-shoulders, and in a swiveled shackle embracing the reduced end of the bolt, and it, like said reduced end, having a series of threaded recesses for 25 gripping the body of the bolt.

Referring to the drawings, Figure 1 is a perspective of a device constructed in accordance with my invention. Fig. 2 is a longitudinal vertical section. Fig. 3 is a transverse view 30 through the pivot; Figs. 4 and 5, details in perspective of the bar or lever and the shackle, respectively.

Like numerals of reference indicate like parts in all the figures of the drawings.

35 The bar 1 is rectangular in cross-section and of a desired length, and has its rear edge chamfered or cut away, as at 2, forming a tooth 3. The opposite end is reduced at opposite sides, as at 4, and provided at its extremity with a series of curved recesses 5, threaded and formed upon various-sized arcs. In rear of the reduced end 4 the under side of the bar 1 is provided with a protrusion forming a fulcrum-point 6. A transverse bolt-opening 7 is formed in the bar above the fulcrum 45 6, and in said opening there is mounted a transverse bolt 8.

9 represents a U-shaped shackle, the terminals of which are near their ends provided 50 with bolt-openings 10, agreeing in size with

that formed in the bar 1. This shackle is mounted upon the bolt 8, and the latter is provided at its threaded end with a binding-nut 11. The inner edge of the shackle, or that portion thereof opposite the reduced ends 4, 55 is provided with a series of threaded variously-sized curved recesses 5, said recesses being located opposite to and agreeing in size with the recesses 5, formed in the oppositely-reduced end 4 of the bar 1. 60

The manner of using the invention is as follows: The reduced rear end 3 is first inserted under the head of a bolt, and by using the bar 1 as a lever said bolt is slightly elevated from the hole in which it is located. This 65 operation is carried on until the bolt has been raised from a half to three-quarters of an inch, when the bar 1 is turned around or reversed and swung upon the bolt 8 until at substantially a right angle to the shackle, when the 70 device is lowered so that the shackle takes over the head of the bolt. The rear end of the bar 1 is now lowered until it bites upon the body of the bolt, the protrusion 6 acting as a fulcrum. By bearing down on the rear 75 end of the bar 1 the bolt is withdrawn gradually, and when the bar 1 has been depressed a few inches a new hold upon the bolt is taken by repetition of the operation just described—namely, swinging the rear end of the bar up 80 and slipping the shackle lower down upon the bolt to be extracted. In this manner bolts may be withdrawn with ease and facility from their respective openings. The under surface of the shackle is rounded, so as to rock in accordance with the movements of the bolt in the act of withdrawal, and the recesses 5 are somewhat slanting, so that the recesses are always substantially parallel with the bolt upon which it is operating, and thereby afford a seat for the bolt that has contact with the bolt for a considerable portion of the length of the bolt. 90

Having thus described my invention, what I claim is—

1. In a device of the class described, a bar reduced at its forward end and provided with a series of variously-sized curved bolt-receiving recesses and in rear thereof a transverse bolt-opening, in combination with a shackle of U 95 100

shape, the terminals of which embrace the bar and are provided with a bolt-opening, and a bolt passed through the opening and through the bolt-opening of the bar and provided with 5 a nut, said shackle having its inner edge recessed to correspond with the recesses of the bar, substantially as specified.

2. The bar 1, reduced at its rear end, as at 3, at its forward end, as at 4, and having the 10 protuberance 6 upon its under side in rear of the reduced front end, and above the same the transverse opening 7, in combination with the U-shaped shackle 9, embracing the end

of the bar and provided with bolt-openings 10, the bolt 8, and the nut 11, the inner edge 15 of the shackle and the front end of the bar 1 being provided with a series of corresponding grooves or recesses, substantially as specified.

In testimony that I claim the foregoing as 20 my own I have hereto affixed my signature in presence of two witnesses.

CHRISTOPHER COLUMBUS WARREN.
